[57] CLAIM

The ornamental design for an antenna support for model airplane radio transmitters, substantially as shown and described.

DESCRIPTION

FIG. 1 is a top plan view of an antenna support for model airplane radial transmitters showing my new design;

FIG. 2 is a side elevation thereof;

FIG. 3 is a front elevation thereof; and

FIG. 4 is a bottom plan view thereof.

The drawings indicate a contrasting surface on the support legs of my antenna support for model airplane radio transmitters.

FIG. 1

FIG. 2

FIG. 3

FIG. 4
